UNITED STATES PATENT OFFICE.

ALFRED HERBERT GIBSON, OF HARROGATE, ENGLAND.

APPARATUS FOR SUPPLYING LIQUID FUEL TO INTERNAL-COMBUSTION ENGINES AND FOR ANALOGOUS PURPOSES.

Application filed August 25, 1925, Serial No. 52,476, and in Great Britain September 11, 1924.

The invention has reference, primarily, to apparatus for supplying liquid fuel to internal combustion engines, and particularly those of motor vehicles, of the class in which 5 the fuel is drawn by suction from a main supply tank to an intermediate vessel or carburettor from which it is supplied for use.

Apparatus is known in which an air space, within a vessel forming part of a direct suction system, permits of a flow of fuel to an engine during certain running conditions, but such apparatus does not provide for continuity of supply during changing load or accelerating conditions, and for ample 10 reserves of fuel for starting purposes.

If an air space in a vessel will only ensure a continuous flow of fuel during certain running conditions of an engine, it cannot serve any useful purpose. In fact, a direct 15 suction feed without any intervening air space would be more advantageous.

The present invention ensures a continuous flow of fuel to the engine during changing load or accelerating conditions and the 20 formation and maintenance of ample reserves 25 of fuel for starting purposes.

The invention is characterized in that in a conduit system between a spraying orifice or orifices or point or points of fuel delivery 30 to the engine, and a supply tank having a vent open to atmosphere, there are included one or more stationary but elastic air breaks 35 constituted in vessels or enlargements forming part of the system, through or from which vessels or enlargements a continuous supply 40 of fuel is drawn, whilst the engine is running, solely by the suction exerted through the passage or passages by which fuel is delivered to the engine, means being provided whereby, 45 before the fuel level in a reserve vessel can sink below the mouth of the outgoing duct or ducts, such a degree of attenuation is produced in the air break as to cause inflow of fuel to such vessel at a volume rate not less than that of the outflow therefrom.

The invention contemplates, and is principally designed for, the maintenance of a fuel supply from a storage tank disposed at a substantially lower level than the intake 50 to the engine, but it can be applied to cases where the storage tank is at the same level as or at a higher level than the fuel intake to the engine.

It is obvious that the invention may be utilized for supplying to the engine or its 55 parts liquids other than fuel, such as lubricating oil or water. It is also obvious that when two or more different fuels, water or other liquids are desired to mix in certain proportions at any point or points in the conduit system, the desired proportions may be obtained by suitably regulating the relative 60 backward drags on the various liquids at the common point or junction of suction.

The invention will be described with reference to the accompanying drawings which illustrate diagrammatically several alternative types of construction. Though for the purpose of illustration, only one fuel duct is shown leading to and from a reserve vessel, 65 any number of ducts may be provided, and one of them may supply fuel for idling or slow running of the engine. Any fuel duct may sub-divide into two or more branches. Any fuel duct may lead from the top, sides 70 or bottom of a reserve vessel, provided the conditions required by the invention are obtained. When a construction is used in which, on stopping the engine, the fuel in 75 a reserve vessel would flow back to the main supply tank, a non-return valve is obviously provided to prevent such backward flow. The invention is not confined to the use of only one reserve vessel nor to positioning a reserve vessel close to the intake of the engine, and any reserve vessel may be of multiple form or may have two or more compartments.

The invention will be described with reference to the accompanying drawings wherein 80

Fig. 1 is a diagrammatic illustration of 85 one form of the invention, in which provision is made for the creation of two fuel reserves between a supply tank and the point or points of delivery to the engine.

Figs. 2 and 3 are diagrammatic illustrations showing modifications.

Referring to Fig. 1, *a* represents a main supply tank usually positioned at the rear 100 of a motor vehicle, and *b* a reserve vessel located on or adjacent to the instrument board. The tank *a* has a vent *a'* open to the atmosphere, and the vessel *b* is assumed to be closed to the atmosphere. A pipe *d* connects the tank *a* with vessel *b*, and a pipe *e* extending 105 well down into the vessel *b* connects the

said vessel with the carburetor or fuel inlet (or other point of liquid delivery which is under sub-atmospheric pressure so that the sub-atmospheric pressure extends into said conduit or pipe *e*) to the intake of the engine (disregarding for the present the second vessel *c* and pipe *f* hereinafter referred to). In this pipe *e* is a valve *e*¹ opening in the direction of suction and functioning to trap 10 in the vessel *b* a negative or sub-atmospheric pressure when the engine is stopped after running, and functioning further to ensure that immediately fuel commences to flow from the vessel *b* on restarting the engine, fuel immediately commences to flow into the vessel to replace that withdrawn.

Assume the apparatus commencing to work for the first time after its installation on a motor vehicle, the tank *a* containing a supply of fuel and the vessel *b* having been filled by hand with fuel up to a level much above the mouth or inlet end of the pipe *e* but leaving an air space represented by *A*, then the action of the apparatus is as follows:—

25 On engine suction being applied to the pipe *e*, fuel is drawn from the vessel *b* through the pipe *e*. The withdrawal of fuel causes the air in the vessel *b* and the air in the pipe *d* to become attenuated with the result 30 that fuel rises to the vessel *b* from the main supply tank *a*. The engine will now continue to run with a continuous unbroken supply of fuel so long as there is fuel in the tank *a* to supply the vessel *b*. On stopping 35 the engine, the valve *e*¹ in the pipe *e* closes automatically by the difference in pressures on its two sides, and in so closing traps negative pressure in the vessel *b*. The fuel level in the vessel *b* is now at a lower level than 40 when the vessel was first filled manually, but is still above the level of the mouth of pipe *e*, and it will not fall below such mouth in subsequent runnings of the engine. The extent of rise and fall of the fuel level in 45 the vessel *b* and the degree of attenuation in the air space above the fuel during changing load or changing speed of the engine will depend on backward drag forces and resistances in the pipe *d*. On restarting the engine, fuel will commence to flow through 50 the pipe *e* as soon as the suction force equals the trapped depression in vessel *b*, after making allowance for any head or drag due to fuel trapped in pipe *e*. The valve *e*¹ may 55 be positioned at any point in the pipe *e*, and the pipe itself may be connected to and extend downwardly from the lower part of the vessel *b*, the trapped depression in the vessel preventing, when the engine is stopped 60 running, any leakage of fuel from the vessel, suitable provision being made to prevent fuel flowing from the vessel during manual filling.

The form of apparatus as thus far de-

scribed with reference to Fig. 1 works fairly 65 satisfactorily in practice, but defects may arise through any of the following causes:—

(1) Expansion of the air space in the vessel *b* due to heat radiated from the engine and vaporization of fuel.

(2) Slow air leakages into the conduit system reaching the vessel *b*.

(3) The valve *e*¹ not closing properly when the engine is stopped running, owing to the presence of foreign matter in the fuel.

Provision is made to ensure that whilst the engine is running the air pressure in any fuel reserve vessel is quickly adjusted to a degree sufficient to draw fuel to such vessel at required changing rates of inflow without any great change taking place in the level of the fuel in the vessel such as might uncover the mouth of the main fuel duct. This provision may take several forms. As shown in Figs. 1 and 2, it takes the form 85 of an air absorbing hole or passage in the pipe through which fuel flows from the reserve vessel. In Fig. 1 the pipe *e* proceeds upwardly from the vessel *b*, but it has in it a small hole *eh* positioned well above the bottom mouth or lower end of the pipe. It is essential that this hole be very small as compared with the bore of the pipe *e*, to ensure that when the hole is uncovered fuel 90 shall continue to rise through the bottom mouth of the pipe *e*. Whilst the engine is running and absorbing fuel through the bottom mouth of the pipe *e*, any tendency for the fuel level to fall materially below the hole *eh* is quickly arrested by small quantities of air being drawn through such hole and mixing with the fuel passing through pipe *e*. The rapid increase in negative pressure in the space *A* due to the extraction 95 of air in the manner just described accelerates inflow of fuel to the reserve vessel, and as soon as the fuel level has again covered the hole *eh*, further absorption of air through such hole ceases until the hole is again uncovered. The air absorbing hole may, if desired, be in the form of a small mouth to a branch pipe joining up, inside or outside the vessel *b*, to the pipe *e* or it may take the form of a very narrow slit. More than one air absorbing hole may be employed if desired. When an air absorbing hole or passage is covered by fuel it is obvious that fuel 100 will be absorbed through it instead of air.

In Fig. 2 the pipe *e* extends upwardly into the vessel *b*. In this construction it is essential that the bottom hole or passage *ex*, which acts in this case as the main fuel mouth in the pipe *e*, should be small in order that some of the suction transmitted through the pipe *e* may be felt at its top mouth in order to maintain the fuel level at or near the level of such mouth by absorption of small quantities of air through the mouth when

not covered by fuel. A valve such as e^1 , Fig. 1, may also be used in this last described construction.

In constructions embodying the air absorption principle, such as illustrated by Figs. 2 and 3, a priming charge of fuel to the engine may obviously be released from a reserve vessel by a temporary admission of air.

10 Fig. 1 illustrates a second vessel c into which the pipe e discharges, the same as the pipe d discharges into the vessel b , and a pipe f extends from within the vessel c in order that the second vessel c will function similarly to the vessel b providing the pipe f is provided with a suction opened valve similar to the valve e^1 . It is thus possible to employ a series of the vessels in the conduit, but same may not be desired in some instances, and so 20 far as the apparatus shown in Fig. 1 is concerned, the pipe e may communicate directly with the engine at a point of liquid delivery which is under sub-atmospheric pressure. Fig. 1 also shows a check valve d^1 in the pipe d to prevent reverse flow.

If the main supply tank be positioned above the level of the delivery point or points to the intake of the engine, the air break or space above referred to can still be made to perform its required functions, but in order that siphonic flow may not take place when the engine is stopped it is preferable that the air break should extend from a position materially above the level of the fuel in the main tank 30 to a position very near to the level of the fuel intake to the engine. If the air break commences from a position about the level of the bottom of the main supply tank, it is desirable that it should extend to a position well below 40 the level of the fuel intake to the engine. A long air break prevents siphonic flow by breaking up a drag fall due to molecular attraction. The construction adopted and the positioning and dimensions of the air break 45 not only determine whether there will be any siphonic tendency or not when the engine is stopped, but also the degree of air or vapor pressure in the air break space. Some constructions give rise to negative pressure in the 50 air break and others to positive pressure, when the engine is running, and the degree of pressure varies with the forces to be overcome in drawing fuel at the required rate from the main supply tank. Where positive pressure 55 is existent in an air break when the engine is not running, depression, when the engine is running, may or may not cause such pressure to change over to a negative state. In other words, the positive pressure of an air 60 break may be subject to a certain depression and yet remain in a position state, but of lesser or reduced degree. When no regard is given to the positioning of the air break, it may be necessary to safeguard against siphonic action, when the engine is stopped, by placing 65

in the fuel circuit a lift resistance, the resisting effect of which increases with increasing downward gradients, or to stop siphonic flow action by the admission of air at an appropriate point provided the admission of such air will not release a trapped depression in a reserve vessel. The employment of a lift resistance is equivalent to disposing the main tank at a level below the point or points of fuel delivery to the intake to the engine. 70

75 Fig. 3 illustrates one type of construction to prevent siphonic flow action when the engine is stopped running in a case where the supply tank, as above mentioned, is situated above the level of the fuel delivery to the intake of the engine. 80

To compensate, wholly or partly, for variation in fuel lift or fuel head when a motor vehicle is proceeding uphill or downhill, there may be employed in the circuit a resistance or resistances arranged to increase or decrease in effect according to the inclination of the vehicle from the horizontal. Such a resistance may comprise one or more metal balls j , as seen in Figs. 1 and 2, or a weighted flap or 85 needle valve subject to the action of gravity and which will operate automatically. If preferred, however, a manually-operable resistance or resistances may be employed. The balls j or other gravity corrective resistance 90 are so arranged that when the vehicle is travelling on inclines so as to raise or lower the main supply tank with reference to the delivery point of fuel, such resistance will be increased or decreased in proportion. Thus, when the supply tank is raised with reference to the point of fuel delivery the balls or other means may be moved toward a vertical position in order to increase the gravity effect and 95 resistance thereof, and vice versa. 100

105 According to the position and resisting effect of the above named or any other resistance in the fuel conduit, so will an enclosed air space permit of different degrees of acceleration of an engine. 110

115 A valve such as e^1 , Fig. 1, may be employed in any construction adopted, and when two or more fuel pipes lead from a reserve vessel, or a fuel pipe connects to the fuel intake of the engine by two or more branch pipes, such a valve may be provided in each or any pipe or branch to ensure a continuous flow of fuel to the engine whilst it is running notwithstanding that one or more of the pipes or 120 branches may not be under the influence of engine suction at certain throttle openings.

125 A controlling cock or cocks or other means to regulate the rate of fuel flow may be provided at any convenient point in the system. The flow of fuel may be partly regulated by the admission of air to the conduit either at or near the highest point in the conduit or between that point and the point of fuel delivery to the engine, and the admission of such air may be made variable and dependent 130

upon movement of the engine throttle or throttles. Air may not, however, be admitted to or before a reserve vessel except in the case of constructions of the type *b* illustrated by Figs. 1, 2 and 3, embodying the air absorption principle.

In case the main supply tank should become emptied of fuel and the system filled with air, it is desirable that reserve vessels 10 be provided with filling orifices closed by suitable caps. Drain cocks may also be provided.

Although the use of floats in a fuel feed system is to be avoided where possible, a float 15 may be used in any construction in which it may be found advantageous.

The invention obviates necessity for the use of a separate non-fuel conveying suction pipe connected to the induction system of an engine for the purpose of raising fuel from a 20 low level supply tank. If such a separate suction pipe were added to apparatus according to the invention it would afford no advantage.

Having thus described my invention, what 25 I claim as new and desire to secure by Letters Patent is:—

1. A liquid supply apparatus for an internal combustion engine comprising a liquid supply tank having an air entry vent, a liquid 30 conduit leading from the tank to a point of liquid delivery which is under sub-atmospheric pressure so that the sub-atmospheric pressure extends into said conduit, said conduit having a liquid reserve vessel therein 35 through which the liquid flows, said vessel having a liquid inlet and a liquid outlet and an air space above the liquid outlet, in order that said air space will permit of attenuation 40 of the air therein when the liquid is drawn by said sub-atmospheric pressure from the vessel so that said air attenuation will draw liquid into the vessel from said tank, said liquid inlet and outlet of the vessel being at higher and lower levels than said tank.

2. A liquid supply apparatus for an internal combustion engine comprising a liquid supply tank having an air entry vent, a liquid conduit leading from the tank to a point of liquid delivery which is under sub-atmospheric pressure so that the sub-atmospheric pressure extends into said conduit, said conduit having a liquid reserve vessel therein 50 through which the liquid flows, said vessel having a liquid inlet and a liquid outlet and an air space above the liquid outlet, in order 55 that said air space will permit of attenuation of the air therein when the liquid is drawn by said sub-atmospheric pressure from the vessel so that said air attenuation will draw liquid into the vessel from said tank, a portion of said conduit being inclined, and gravity acting means in said inclined portion of the conduit operable to increase and decrease the resistance to the flow of liquid 60 through the conduit when said apparatus is tilted to increase and decrease the angle of inclination of said portion of the conduit, respectively.

that said air space will permit of attenuation of the air therein when the liquid is drawn by said sub-atmospheric pressure from the vessel so that said air attenuation will draw liquid 60 into the vessel from said tank, the portion of said conduit leading from said vessel having a restricted air hole in said vessel at a higher level than the liquid outlet to permit air to be withdrawn from the vessel before 65 the liquid level therein falls to said liquid outlet.

3. A liquid supply apparatus for an internal combustion engine comprising a liquid supply tank having an air entry vent, a liquid 70 conduit leading from the tank to a point of liquid delivery which is under sub-atmospheric pressure so that the sub-atmospheric pressure extends into said conduit, said conduit having a liquid reserve vessel therein 75 through which the liquid flows, said vessel having a liquid inlet and a liquid outlet and an air space above the liquid outlet, in order that said air space will permit of attenuation of the air therein when the liquid is drawn by 80 said sub-atmospheric pressure from the vessel so that said air attenuation will draw liquid into the vessel from said tank, said liquid inlet and outlet of the vessel being at higher and lower levels than said tank.

4. A liquid supply apparatus for an internal combustion engine comprising a liquid supply tank having an air entry vent, a liquid conduit leading from the tank to a point of liquid delivery which is under sub-atmospheric pressure so that the sub-atmospheric pressure extends into said conduit, said conduit having a liquid reserve vessel therein 90 through which the liquid flows, said vessel having a liquid inlet and a liquid outlet and an air space above the liquid outlet, in order that said air space will permit of attenuation 95 of the air therein when the liquid is drawn by said sub-atmospheric pressure from the vessel so that said air attenuation will draw liquid into the vessel from said tank, a portion of said conduit being inclined, and gravity acting means in said inclined portion of the conduit operable to increase and decrease the resistance to the flow of liquid 100 through the conduit when said apparatus is tilted to increase and decrease the angle of inclination of said portion of the conduit, respectively.

In testimony whereof I affix my signature.

ALFRED HERBERT GIBSON.
